Harry B. Schiller

ATTORNEY:

UNITED STATES PATENT OFFICE.

HARRY B. SCHILLER, OF PHILADELPHIA, PENNSYLVANIA.

WRENCH.

No. 801,919.

Specification of Letters Patent.

Patented Oct. 17, 1905.

Application filed March 8, 1905. Serial No. 248,196.

To all whom it may concern:

Be it known that I, HARRY B. SCHILLER, a citizen of the United States, and a resident of the city of Philadelphia, State of Pennsylvania, have invented certain new and useful Improvements in Wrenches, of which the following is a full, clear, and complete disclosure.

An object of my invention is to produce a wrench having an adjustable jaw to enable 10 the same to be adapted to different sizes of nuts, bolts, &c., said jaw being provided with means which allow it to be quickly and easily adjusted, and when so adjusted the jaws will be held firmly and rigidly in position without any tendency to slide or become distorted.

A further object of my invention is to simplify the structural parts, so that the liability of the same to break is reduced to a minimum and so that the cost of manufacture is made 20 as low as possible. For a full, clear, and exact description of this form of my invention reference may be had to the following specification and to the accompanying drawings, forming a part thereof, in which—

25 Figure 1 is a perspective view of my improved wrench. Fig. 2 is a longitudinal sectional view thereof, taken through the movable or adjustable jaw; and Fig. 3 is a sectional view taken substantially upon the line 30 3 3, Fig. 2.

Referring to the drawings, the numeral 1 indicates a shank or handle which is provided at one end with a fixed jaw 2, extending at substantially right angles to the shank 35 1 in the usual manner. These parts are preferably made integral with each other, and the shank 1 is of substantially the same thickness throughout, but varies slightly in width from the upper end A to the lower end B, where 40 it is slightly wider. The variation in width of the handle or shank 1 is about one thirty-second of an inch for a wrench having a shank six inches long, or, in other words, the difference in width is about one-sixteenth of an 45 inch to a foot.

The movable jaw 3 is provided with the usual slot or opening 4, and the projecting portion of the jaw 3 opposite the jaw 2 is provided with a socket or recess 5, which is provided with an inclined inner wall, the said 50 wall and shank or handle converging toward each other as they extend away from the face of the jaw, as indicated at 6. The inclination of the inner wall of the socket is preferably 55 about one-eighth of an inch for a jaw one inch and a half wide, but may be made more or

less, according to special design and use. The side walls of the recess 5 are preferably parallel, and the lower end of the recess is preferably not provided with any integral or fixed 60 wall, as indicated at 7. Within the recess 5 is placed a wedge-shaped or tapering block 8, which is adapted to slide easily therein between the parallel side walls of the recess. The block 8 is provided with a screw-threaded 65 hole 9, which is engaged by a thumb-screw 10, said thumb-screw preferably having a slideable cross-bar or lever 11, which passes through an opening in the head of said screw. When the lower end of the recess is not provided with an integral or permanent wall, I 70 attach a bearing-plate 12, against which the head of the screw 9 is adapted to rest and when said screw is tightened will cause the block or wedge 8 to be drawn outwardly 75 toward said plate.

It will be noted that the surfaces of the shank are smooth and have no serrations or corrugations by which the movable jaw 3 is held in position, said movable jaw being held entirely 80 by friction, thereby obviating the necessity of disengaging the teeth of such serrations or corrugations when it is desired to adjust the jaws of the wrench. It will also be noted that when pressure is brought to bear upon the 85 jaw 3 any slight movement of said jaw, should the screw 10 not be sufficiently tightened, would tend to more firmly wedge the block 8 against the shank 1, and thereby prevent said jaw from having further movement. 90

By making the taper of the shank and the taper of the recess in opposite directions any motion of the block 8 away from the jaw has immediately a wedging effect on both sides against the inner wall of the recess and against 95 the shank, thus enabling the jaw to be quickly and securely clamped in any position. Moreover, by drawing the block outwardly away from the clamping-jaw I am enabled to use a smaller screw than would be necessary if it 100 were used to thrust the block forward and to use an ordinary plain machine-screw instead of a specially-shaped screw with abutting collars or shoulders. My construction, therefore, combines a quick adjustment, a light construction, and a secure binding of the jaw to the shank or handle.

I am aware that wrenches have heretofore been made which involve the use of a tapering shank, and I am also aware that wrenches have 110 heretofore been made involving the use of a wedge or tapering block for holding the mov-

able jaw in position in connection with serrations or corrugations on the shank or handle of the wrench; but the combination and construction herein set forth I believe to be entirely original with me, and

Therefore, what I claim, and desire to protect by Letters Patent of the United States, is—

1. An adjustable wrench having a shank or handle, the edges of which converge toward the fixed jaw on the extremity thereof, a movable jaw located upon said shank or handle, said jaw being provided with a tapering wedged-shaped groove or recess, the taper of which is toward the said shank in a direction away from the face of the jaw, a tapering or wedged-shaped block located within said groove or recess, and a means for drawing said block toward the small end of said recess.
2. An adjustable wrench having a plain shank or handle, the plain edges of which converge toward the fixed jaw on the extremity thereof, a movable jaw located upon said shank, said movable jaw being provided with a tapering or wedged-shaped groove or recess, the tapering side of which converges toward said shank in a direction away from the face

of said jaw, a plain tapering or wedged-shaped block located within said groove or recess and adapted to bear against said shank and a screw 30 for drawing said block toward the small end of said recess.

3. An adjustable wrench having a plain shank or handle, the plain edges of which converge toward the fixed jaw on the extremity 35 thereof, and a movable jaw located on said shank or handle, said movable jaw being provided with a tapering or wedged-shaped open-ended groove or recess, the inclined side of which converges toward the shank in a direction away from the face of the said jaw, a plain tapering or wedged-shaped block fitted within said recess, and adapted to bear against said shank, a plate adapted to close the end of 40 said slot or recess and a screw passing through 45 said plate for drawing said block outwardly toward the smaller end of said recess.

In witness whereof I have hereunto set my hand this 1st day of March, 1905.

HARRY B. SCHILLER.
